UNITED STATES PATENT OFFICE.

WILLIAM J. COOK, OF CHARLOTTE, NORTH CAROLINA.

ELECTRIC-CIRCUIT CLOSER.

1,382,476.

Specification of Letters Patent. Patented June 21, 1921.

Application filed October 10, 1919. Serial No. 329,714.

To all whom it may concern:

Be it known that I, WILLIAM J. COOK, a citizen of the United States, residing at Charlotte, in the county of Mecklenburg and State of North Carolina, have invented new and useful Improvements in Electric-Circuit Closers, of which the following is a specification.

This invention relates to circuit closers commonly known as push buttons, and one object is to provide an improved construction wherein the active parts are free for operation and sticking or jamming is practically impossible. Another object of the invention is to provide an improved construction of contact embodying means for effecting adjustment to take up or compensate for wear and also to insure a reliable engagement of the circuit making members. A still further object of the invention is to improve the construction of push button disclosed by my Patent No. 1,245,570, dated November 6, 1917, by materially reducing the number of parts involved in the button organization of said patent and producing a plunger having a contact block of such form and arrangement that it will always positively engage a preferred form of contact members for the wire terminals and be self-cleaning with material advantages in providing a good metallic connection and reducing repair and cleaning manipulations to a minimum.

With these and other objects and advantages in view the invention consists of the construction and arrangement of the several parts which will be more fully hereinafter described and claimed.

In the drawing:-

Figure 1 is a sectional elevation, showing my improved form of push button applied for use, as for example, in an elevator.

Fig. 2 is a front view of the parts shown by Fig. 1.

Fig. 3 is a longitudinal vertical section of the improved push button showing the parts in position for making a circuit.

Fig. 4 is a longitudinal vertical section of the improved button taken in a plane at right angles to that shown by Fig. 3 and showing the parts in normal position.

Fig. 5 is a rear end elevation of the improved button.

The improved push button or circuit closer comprises a base plug 5 of suitable form and composed of insulating material.

The plug 5 has an end flange 6 and a central bore 7 extending completely therethrough, the said bore being diametrically enlarged at opposite extremities of the plug to form seats 8 and 9. The seat 8 is of greater diameter than the seat 9 and the side wall thereof is screw-threaded to receive a suitable metal socket 10 having one end 11 fully open and the opposite end 12 closed with the exception of a central opening 13 which aligns with the bore 7, and the seat 9 has a smooth side wall 14. The exterior of a portion of the plug 5 is screw-threaded to receive and secure an inclosure or casing body 15 which is similarly screw-threaded and preferably cylindrical, the said body being formed of metal and having a flanged head 16 thicker than the said body and provided with a central opening 17. Within the opening 17 a button 18 of the usual material is movably mounted and normally projects outwardly beyond the outer side of the head 16. The button 18 is limited in its outward movement by an inner flange 19 forming a part thereof and adapted to bear against the inner side of the head 16 around the opening 17. A screw-threaded seat 20 is formed in the center of the button 18 and opens through the inner end thereof, and in this seat an exteriorly screw-threaded metal socket 21 or insert is mounted and provided with a threaded bore 22 extending partially therethrough, the said bore of the socket opening through its inner end. The outer screw-threaded end 23 of a plunger 24 having a rear terminal contact head or block 25 is secured in the threaded bore 22 of the socket 21, said plunger being freely reciprocable through the center of the socket 10, opening 12 of the latter and bore 7 of the plug 5. Between the bottom 12 of the socket 10 and the inner end of the socket 21 a spring 26 is interposed and surrounds the plunger 24 and operates to normally retract or throw out the button 18, plunger 24 and head 25 when the said button is relieved of pressure. The head 25 is normally positioned in the seat recess 14 at the center of the inner end of the plug 5 and secured to the rear side of the said plug and its flange 6 at opposite points are metallic conducting strips 27 having inner preferably overlapping yielding angular contacts 28 and 29 which are normally separated but are brought into circuit making engagement by pressure of the plunger head 25 there-

against. Circuit wires 30 and 31 are attached to the strips 27 and may be electrically connected to any device or devices adapted to be operated by the improved 5 push button or circuit closer.

Among many advantages of the improved push button relatively to the structure disclosed by my patent are, a materially reduced number of parts and a consequent reduction in cost of manufacture and a simplified assemblage; the certainty of positive engagement of the plunger head 25 with the contacts 28 and 29; the self-cleaning of the head 25 by its wiping action relatively 10 to the contacts 28 and 29 to thereby insure a more perfect electrical contact engagement and reduce the necessity of frequent repair and manual cleaning of the said engaging parts, and the readiness of adjustment of 15 the head 25 to compensate for wear and which is accomplished by exteriorly rotating the button 18 in the proper direction to move the plunger 24 and head 25 a greater distance inwardly without disorganization 20 of the parts of the improved device. It will be seen that the adjustment of the parts to compensate for wear is accomplished by direct actuation or rotation of the head 25 without requiring a separation of any of the 25 parts of the improved push button, and this adjustment may be effected by anyone while the improved button is installed and without requiring special mechanical ability or electrical knowledge and whereby the button 30 may be maintained in positive operating condition. The shape and arrangement of the contacts 28 and 29 will always insure a positive engagement of the one contact with the other by pressure of the head 25 there- 35 against, and moreover, the head 25 can never become displaced relatively to the said contacts 28 and 29. The yielding action of the contacts 28 and 29 also provides for an easy movement limiting action of the button 40 and plunger 24 and its head 25 when the latter parts are depressed to make or complete an electrical circuit in which the improved device is included and prevent the remaining parts of the device being subjected 45 to shock or jar.

What is claimed is:—

1. A circuit closer of the class specified, comprising an inclosing casing, an insulating plug held within the casing, conducting strips secured to the rear end of the plug for attachment of the circuit wires, the conducting strips having their free extremities inwardly bent at an angle and overlapped and normally out of engagement, and a spring 55 actuated plunger mounted in and movable through the plug and having an outer threaded end with a head thereon which

serves as an actuating means for the plunger and is directly rotatable relatively to the plunger to adjust the latter without disorganizing the parts of the closer, the rear end of the plunger having a head to effect an engagement of the said angular contacts. 65

2. In a circuit closer of the class specified, an insulating plug having a rear flange and a central bore, an inclosing casing secured to the plug having a flanged head with a central opening therein, a spring controlled plunger movably extending through the bore of the plug and having a contact head on its rear end, resilient conducting strips secured to the rear end of the plug and having inwardly extending overlapping contact members normally out of engagement and located at a distance from the rear outlet of the plug bore for engagement by the said plunger head, and a button freely depressible and rotatable in the said opening of the flanged head of the casing and directly secured to and adjustably engaging the outer end of the plunger whereby the latter and contact head on the rear end thereof may be adjusted by rotating the said button to compensate for wear without disorganizing the parts of the closer. 70 75 80 85 90

3. In a circuit closer of the class specified, an insulating plug having a central bore opening into a front seat of larger diameter than the bore, the casing secured to the plug and having an outer head with an opening therethrough, a socket mounted in the said front seat of the plug, the plug also having a rear enlargement forming a seat recess, a spring controlled plunger movably mounted in said plug bore and provided with an outer threaded end and a rear contact head movable into the rear seat of the plug, yielding conducting strips secured to the inner end of the plug and having inwardly projecting overlapping angular contacts which are normally separated and adapted to be engaged by the plunger contact head, and a button movably mounted in the head opening of the casing and having a threaded insert opening through the inner end thereof to adjustably receive the outer threaded end of the plunger and whereby by direct rotation of the said button the plunger with its contact head may be adjusted to compensate for wear and insure positive engagement and operation in conjunction with the said angular contacts of the conducting strips. 95 100 105 110 115

In testimony whereof I have hereunto set my hand in presence of two subscribing witnesses.

WILLIAM J. COOK.
